Application January 24, 1938, Serial No. 186,635
In Great Britain February 2, 1937

46 Claims. (Cl. 149—17)

This invention relates to machines for treating hides and skins. While the invention is illustrated as embodied in a machine for staking light leathers, it is to be understood that the invention and various important features thereof may have other applications and uses.

In staking operations with machines as heretofore constructed, the operator has had difficulty in exercising the desired control of the 0 staking operation, particularly in the direction of suiting the pressure of the staking tools to different classes of work or to different portions of the same piece of work. Furthermore, in most cases, he has been unable to avoid tearing marginal portions of skins, and other portions having holes or tears therein. As a result, it is not uncommon for the operator of a staking machine to fill a good sized barrel with torn off portions of staked skins every week or so.

20 Accordingly, it is an object of this invention to provide a machine which will be easily controlled by the operator to suit staking operations to various classes of work and to different portions of the same piece of work. It is a further object of the invention to provide a construction which may be readily adjusted to predetermine the staking pressure upon various portions of the same piece of work, without sacrificing immediate control of the pressure of the staking operation by the operator as in prior art constructions.

30 It is an important feature of the invention that means is provided for enabling the operator to predetermine the character and direction of an increased staking pressure or, alternatively, of a decreased staking pressure as the staking tool operates progressively on various portions of a given piece of work. In other words, the operator may so condition the staking machine that the machine will automatically increase the 40 staking pressure from a central portion of a skin to an edge portion thereof. Alternatively, he may readily condition the machine so that it will automatically decrease the staking pressure from a middle portion of the skin where staking begins to an edge portion thereof. Whether the staking pressure should remain the same throughout the stroke of the tools or progressively increase or progressively decrease from a central portion to an edge portion of a given skin will 50 depend upon the characteristics of that skin and the purposes for which it is to be used. In addition, the operator may exercise direct control of the staking operation to increase or decrease the staking pressure in accordance with

his judgment of the requirements of a given piece of work.

A further important advantage of the machine of my invention is found in the fact that the operator may control initiation of the clamping of 5 a work piece as a preliminary to staking operations thereon, after insertion of the work piece into a machine wherein operation of the staking tools is also directly controlled by the operator. To this end, a single manually controllable member, 10 such as a treadle, is provided with connections for controlling the clamp operating means and also the tool operating means, in an organization wherein the clamping means is power operated in such manner as to insure clamping 15 action before the staking tools engage the work piece.

In the illustrated construction, the staking tools reciprocate back and forth in spaced work receiving position until the treadle is depressed 20 by the operator to initiate a staking operation. Hence the operator may introduce a piece of work at any point in the back and forth movement of the tools and determine the beginning and the length of the effective stroke of the 25 staking tools. In other words, he may terminate the staking operation at any point in what would otherwise be the normal operative stroke of the tools. This enables the operator to avoid holes 30 in the work piece and to terminate the operation of the tools at will.

In a preferred embodiment of the invention, the staking tools are carried by a pair of arms which are pivotally mounted on a carriage by which the arms may be reciprocated back and forth during staking operations, a member being provided to connect the arms positively to each other so that movement of the one is followed by movement of the other to an equal extent and in the opposite direction, in an arrangement in which spring means is provided for holding the arms apart so that normally there is no staking operation during back and forth movements of the arms. It is an important feature of this construction that cam means is provided under control of a manually operable member for causing the arms to move toward each other whereby the staking tools engage the work piece in a staking operation, the arrangement being such that the operator initiates operation of the staking tools 50 after he has introduced a piece of work in place between the spaced reciprocating tools.

While staking tools of any well-known construction and arrangement may be employed in the organized machine described in the foregoing 55

paragraphs, a preferred construction comprises an upper and a lower blade arranged in overlapping relation and in parallel planes, together with a third blade on the lower staking arm inclined 5 upwardly and forwardly in a plane to intersect the first-mentioned blades, whereby the third blade effects a milder staking action than the other blades. Such construction preferably comprises also rolls on the upper and lower staking 10 arms to press the work piece into the space between the lower blades. Conveniently, one of the rolls is yieldingly mounted and is provided with braking means to limit the yielding and turning movement thereof, thus securing a certain 15 predetermined staking pressure in spite of the yielding of the roll.

These and other important features of the invention and novel combinations of parts will now be described in detail and then pointed out 20 more particularly in the appended claims.

In the drawings,

Fig. 1 is a side elevation, partly in section and with parts broken away for clearness, of a leather staking machine constructed in accordance 25 with the invention;

Fig. 2 is a rear elevation of the machine also partly in section;

Fig. 3 is a side elevation of operating mechanism for staking tools in another embodiment of 30 the invention;

Fig. 4 is a front elevation of a treadle arrangement hereinafter particularly described;

Fig. 5 is a side view of a portion of the leather working means with co-operating elements 35 arranged differently from those shown in Fig. 1; and

Fig. 6 is a view similar to Fig. 5 showing another arrangement of staking tools.

Referring to the drawings, the machine has 40 two side frames 1 and 2, one of which is provided with a bearing 3 (Fig. 2) for a crank shaft 4. On the inner end of the crank shaft 4, an eccentric 5 is mounted which is shaped to actuate a clamp operating lever 6. Attached to this eccentric is a flywheel 7 which carries a crank pin 8. At its outer end the crank shaft 4 is provided with a driving pulley 9. An idle pulley 10 (Fig. 2) is supported by the bearing casting 3. Pivotally connected to the crank pin 8 is a connecting rod 11 (Fig. 1). This connecting rod carries 45 on the end opposite to the crank pin a cam 12 for operating a pair of tool arms 13 and 14, in a construction wherein the connecting rod 11 oscillates on a gudgeon pin 15. The tool arms 13, 50 14 are pivotally mounted on a crosshead or carriage 16 consisting of two plates (Fig. 2) suitably connected. As illustrated, the gudgeon pin 15 is not directly attached to the crosshead or carriage 16 but is carried by levers or links 17 which 55 at one end are connected to the crosshead or carriage 16 by a pivot pin 18. At their other ends the levers or links 17 are joined by a connecting pin 19 pivoted in the upper end of a link 20 which is adjustably connected at its lower end 60 by means of a pin 21 to a treadle 22. Downward movement of the treadle 22 causes the pin 15 to move upwardly, which movement is additional to the horizontal movement which is imparted by the crank shaft 11. The tool arms 13 and 14 are pivotally supported on the carriage or crosshead 16 by pivot pins 23 and 24. Both tool arms are shaped as shown to form bell cranks. 65 The inner ends of these bell cranks are connected by spaced parallel links 25 (Figs. 1 and 2) and by pivot pins 26 and 27 which are of an eccentric 70 75

construction for the purpose of effecting relative adjustment of the said arms 13 and 14 to bring the tools 13a and 14a carried thereby to the desired working distance apart when the arms are closed.

As the two tool arms 13 and 14 are approximately of identical construction and weight, they counterbalance one another through the link and pivot connections 25, 26 and 27. Only a light spring 28 is required to keep a roller 31 on the arm 14 in contact with the cam 12. As shown, the spring 28 is mounted on that portion of the arm 13 which projects downwardly from the pivot pin 23, the mounting comprising a shouldered stud having a portion projecting into the spring 28. At its other end the spring is mounted on a similarly shouldered pin 29 which is screw threaded in a tapped opening through the center of a tie rod 29a fixedly secured to the spaced plates which constitute the carriage 16. The pin 29 may be adjusted to secure the desired tension in the spring 28 and may then be locked in its adjusted position by a lock nut 29b. A further adjusting screw 30 is provided on the crosshead 16. This adjusting screw limits the opening movement of the two tool arms 13 and 14 which takes place after the treadle 22 has been released. It is to be understood that it is possible to lower the pin 15 so far that the cam 12 is brought out of contact with the cam roller 31, in which case 3 the screw 30 becomes the support of the arms 13 and 14. When this is the case the reciprocating movement of the arms 13 and 14 can continue while the opening and closing motion of the arms and staking tools is eliminated, i. e., the tools 3 are rendered inoperative.

In constructing a high speed machine with as low a frictional resistance as possible, the crosshead or carriage 16 is supported on two swing arms 32 and 33. These swing arms are pivoted 40 in the two side frames 1 and 2 at the points 34 and 35 in the corresponding pivot shafts. The front of the crosshead or carriage 16 is supported on the front swing arm 32 at the point 36 in a corresponding pivot shaft, whereas the back of the carriage 16 is supported on the back swing arms 33 at a point in the corresponding pivot pin 18. The points 18, 34, 35, 36 form a parallelogram. Normally the points 18, 34, 21, 19 form a secondary parallelogram within the first. Both 50 parallelograms oscillate together, and if normally the parallelism of the link 20 with the arms 32, 33 is preserved the distance between the tools throughout the work-treating stroke does not change. That is to say, the gudgeon pin 15 follows the same general horizontally arcuate path as the carriage 16 so long as the distance between the points 18 and 19 remains the same as that between the points 21, 34, i. e., with the link 20 parallel to the swing arms 32 and 33. While 60 these conditions are preserved, the tools describe a parallel-sided path, the width of which is determined by the adjustment of the tool arms by the eccentric pins 26 and 27, for the reason that the effect of the cam 12 on the roller 31 remains 65 the same throughout each working stroke of the tool arms.

If, however, the secondary parallelogram is eliminated by varying the length of one of the short sides by adjustment of the pin 21 in a horizontal direction in a slot 21a in the treadle 22, the gudgeon pin 15 and the cam 12, when reciprocated, are automatically caused to move relatively to the carriage 16 and thereby follow a different path, i. e., either an upwardly or downwardly in- 75

clined arcuate path, so that the action of the cam 12 on the roller 31 varies during each working stroke of the tool arms and the tools describe a tapered path, the sides of this are either convergent or divergent rearwardly according to the position of the adjustment pin 21 in the slot 21a in the treadle 22, so that the pressure of the tools automatically varies accordingly. In other words, the cam member 12 has a movement of translation relative to the carriage 16, as well as a rocking movement, both movements taking place during reciprocation of the carriage. This is very advantageous under certain conditions and is especially desirable in the treatment of glove leather in which the body of the leather receives only a light staking action whereas the edges want pulling out harder. As already alluded to, the machine may be conditioned to do this automatically by appropriate adjustment of the pin 21 in the slot 21a in the treadle 22. By adjustment of the pin 21 in a direction away from the shaft 35 (and to the right from the position shown in Fig. 1), each working stroke of the tools will start with a light pressure and finish with a heavy pressure. By adjustment of the pin 21 in the opposite direction (that is, toward the shaft 35) from its central position, the opposite effect, i. e., starting with a heavy pressure and finishing with a light pressure, is achieved. As indicated, the adjustment of the pin 21 in the slot 21a is relatively small, the length of the slot 21a being about one and one-half inches in a machine wherein the length of the link 20 is about twenty-eight and one-half inches.

The invention is not confined to the parallelogram arrangement just described. Another construction is provided when it is desired to utilize the described novel features in a machine with a longer stroke and for heavy work. As illustrated in Fig. 3, it is possible to have the crosshead or carriage 46 supported in or on stationary grooved slidebars one of which is shown at 60, in which case the levers or links 17 will be provided with a cam roller 61 running on a runner path or guideway 62. The guideway 62 is connected with the treadle 22 by connections which comprise bell crank levers 63 and 64, a link 65 having a turnbuckle 65a therein, another bell crank lever 66, and a connecting rod 67, so that the runner path 62 can be raised and lowered by the treadle for the purpose of effecting normal staking movements of the arms 13 and 14 by lifting the pin 15 and cam 12, as previously described in connection with the link 20 and treadle 22. The runner path 62 is arranged in such a manner that, in addition to its position wherein it is parallel to the main guide-bars 60, it can be inclined by being raised or lowered at one end, in order to obtain the variations in pressure at different portions of the stroke of the tools as previously described in connection with the construction shown in Fig. 1. To effect the desired adjustment of the runner path or guideway 62, the treadle 22 is first depressed the normal amount, as determined by the stop screw 53. This lifts the runner path 62 and also stabilizes the bell crank 63. Now by rotation of the turnbuckle 65a, the link 65 is lengthened or shortened thus adjusting the bell crank 64 to lift or to lower the adjacent end of the guideway 62. Lifting the said end of the guideway 62 will automatically cause increased staking effect on the marginal portions of a piece of work, while lowering said end will cause a predetermined milder staking effect on said marginal portions as com-

pared with more central portions of the same piece of work.

There is provided, in conjunction with the staking mechanism previously described, clamping mechanism to hold the leather during each working stroke. The clamping mechanism comprises a clamp bar 37, which is rigidly attached to the two frames 1 and 2 of the machine, and a clamp member 38 (carrying a cushion member 38a) which is movably mounted on a pivot 39. For the purpose of keeping the clamp in the open or work receiving position, a compression spring 40 is provided. Furthermore, on the clamp member 38 is a projecting arm 41 which limits the opening movement of the clamp by contact with a stop 42 (Fig. 1). There is a connection between the clamp member 38, the cam roll lever 6 and the treadle 22 which is provided by a steel wire rope 56, or other suitable flexible member. The wire rope is connected to the clamp member 38 at the point 43. It passes over a rope pulley 44 and over pulleys 44a and 45 on the lever 6 to a lever 46 which is loosely mounted on a shaft 47. A casting 48 is keyed to the shaft 47 and for adjustably tensioning the rope is provided with adjusting screws 49. The shaft 47 passes through the frame of the machine and carries on the outside of the frame a lever 50 (Figs. 1 and 2) which is also keyed to its shaft. This lever 50 is provided with a cam roller 51 operating against a cam segment 52 which is keyed to the treadle shaft 35. On the opposite side of the shaft 35, the cam segment 52 is provided with a screw 53 which limits the movement of the treadle 22 under pressure of the foot and also the movement of the cam 52 in relation to the cam roller 51. The cam lever 6 is provided with a roller 55 which is acted upon by the cam 5. This cam 5 is timed in such a manner that the clamp 38 is closed before the tools on arms 13 and 14 are completely closed by the cam 12 at the beginning of the operative stroke of the tools. The cam lever 6 is further provided with a compression spring 54 for the purpose of keeping the cam roller 55 on the lever 6 away from the cam 5, when the treadle 22 is in the inoperative position. When the treadle is up no movement is imparted to the clamp member 38 which remains up in open or work receiving position under the action of the spring 40. Conveniently the spring 54 is mounted similarly to spring 28, one end of the spring 54 being mounted on a shouldered stud secured to the lower end of the lever 6 while the other end of the spring 54 is mounted on a shouldered set screw 54a adjustable through being screw threaded into a tapped opening in a stud 54b rigidly secured to the machine frame. It will be clear that the set screw 54a may be adjusted to secure the desired tension in the spring 54 and that it may be then secured in its adjusted position by a lock nut 54c.

In operation the clamp functions as follows:

Assume that the treadle 22 and the clamp member 38 are in the normal or inoperative position shown by full lines in Fig. 1. Then, when the treadle 22 is depressed, the cam 52 will move the lever 50 and apply tension to the rope 56. If at this time the cam 5 is in a position to resist movement of the lever 6, that is, with the high part of the cam to the right in Fig. 1, this movement of the treadle downwardly will move the clamp member 38 against the action of the spring 40 to the closed position indicated by dotted lines in Fig. 1. If, at the time of depressing the treadle 22, the cam 5 is not in a position to resist move-

ment of the lever 6, the movement of the treadle 22 will not operate the clamp member 38 to clamping position. Since the spring 54 is weaker than the spring 40, such depression of the treadle 5 will pull said lever 6 into contact with the lowest part of the cam 5 so that the latter as it revolves 10 will close the clamp in properly timed relation to the operative stroke of the staking tools. Thereafter the clamp is opened and closed at every revolution of the crank shaft 4 by the 15 spring 40 and the cam 5 operating in conjunction in timed relation with the reciprocation of the tool arms 13 and 14 which are also opened and closed at every revolution of the crank by the conjoint action of the spring 28 and cam 12.

It will be perceived that the same treadle 22 serves to render both the clamp member and the leather working means operative. This treadle, which is keyed on the shaft 35 together with the 20 cam segment 52, is provided with a counterweight 68 (Fig. 1) (or it may be spring loaded), whereby when the treadle is released the said clamping and staking means are rendered inoperative. Release of the treadle results in movement of the 25 cam 12 downwardly to a position in which it fails to act on the roller 31, thus accounting for the inoperative strokes of the staking tools. Also, release of the treadle permits the spring 54 to move the lever 6 to inoperative position away 30 from the cam 5.

The machine may be provided with an additional treadle so arranged in conjunction with the treadle 22 that the treadle shaft 35 acts as a torsion spring when the treadle 22a is depressed to its downward limit, thereby enabling pressure to be applied yieldingly to the work. Referring to Fig. 4 of the drawings, it will be noticed that the treadle 22 is secured approximately at the center of the shaft 35 in an arrangement wherein the treadle 22 carries the extension for the pivot pin 21. The second treadle 22a is an extension forwardly of the cam segment 52 which is secured to the end of the shaft 35 outside of the frame 1, this treadle being thus provided with a stop screw 53 carried by the cam segment 52 as already described. When the treadle 22a is depressed to its full limit, as determined by the stop screw 53, the pressure of the staking tools can not thereafter be varied and is constant except for the torsional yielding of the shaft 35. On the other hand, when the treadle 22 is depressed the tools can be closed to the extent which the stop screw 53 permits. In addition, however, a heavier load on the treadle 22 45 will cause a further pressure on the staking tools which is permitted by a torsional deflection of the treadle shaft 35. This torsional characteristic of the shaft 35 will also become evident when the treadle 22a is utilized to control the machine, since the cam 12 and the connecting rod 20 may yield downwardly according to the thickness of the leather passing through the tools through torsion in the shaft 35, and therefore a yielding pressure is applied to the work piece 50 which is controlled by the strength or thickness of the treadle shaft.

For the purpose of facilitating the handling of the leather, a table made in two sections 58, 59, is provided on the operating end of the machine. 70 The section 58 is parallel with the tool path while the section 59 is inclined relatively to the section 58. This inclination is to facilitate the entry of the leather under the clamp.

The path of the tools may be generally horizontal, as in the machine shown in the drawings,

or the parts may be so arranged as to have the tools co-operate with an inclined table in place of the horizontal table 58.

Any existing tools and tool holders, such as the staking knives 13a, 14a, and holders, 13b, 14b, shown in Fig. 1, may be used on the arms 13, 14 with or without one or more roller heads. In Fig. 5, however, there is shown an improved combination of tools including two rollers 69 and 70, in holders 71 and 72, respectively, and also front knives 73 and 74 mounted at corresponding angles on the holders 71 and 72, respectively, so as to act with a sharper effect on the leather. Preferably there is also a back knife 75 inclined in the opposite direction to the front knives and at a greater angle on the holder 72 so that the leather can pass between the rollers 69 and 70 in an easier manner to permit the machine to work at a higher speed. The rollers may be made of rubber. Alternatively, there may be provided a roller tool characterized by the feature that the roller is yieldably mounted in its holder, conveniently by means of springs one of which is shown at 76 (Fig. 6) each associated with a block at the adjacent end of the roller within a holder such as 71, although rubber buffers may be provided if desired. Either or both of the rollers, e. g., the upper roller shown in Fig. 6, may be arranged in this way. In another embodiment, a roller tool is yieldably mounted in its holder, e. g., by means of rubber buffers or springs, and characterized by the feature that a braking arrangement is provided in association with the roller whereby when the roller is subjected to pressure and consequently yields, a braking effect is exerted thereon. According to one construction and arrangement (Fig. 6) there are provided in association with collars on the ends of one or of both rollers or the ends of a spindle which project from the roller, brake blocks 78 of wood or other suitable frictional material, the arrangement being such that when the roller yields under pressure, a collar 80 on each end of the roller spindle is pressed against the brake block 78 and a braking effect is thereby achieved. The greater the pressure applied to the roller in use the greater the braking effect obtained, for which reason the torsion applied to the leather can be regulated according to the pressure applied to the roller.

The improvements hereinbefore set forth provide a machine of the type herein described wherein the jaws or tool arms of the leather working means are caused to move to and fro in unison during the reciprocating motion and such movement is completely under the control of the operator. Furthermore, the pressure applied during working strokes of the tools can be made to vary automatically without any particular attention or the exercise of especial skill on the part of the operator, this being especially advantageous in the staking of glove leather. An especially advantageous arrangement is found in the work gripping or clamping mechanism which, while adapted to be opened and closed automatically in synchronism with the opening and closing movements of the leather working means, when such means are in operation, can also be opened conjointly with the leather working means irrespective of the stage of the reciprocating motion of the latter, since the clamping means is also under the control of the operator. By reason of the last-mentioned facts the leather can be inserted into the machine without fear of it being caught prematurely by the leather

working means, and especially without having to time the insertion, because, after the leather has been placed on the table and a treadle or other operating member is moved operatively to a predetermined extent, the work gripping or clamping mechanism is the first to come into operation to hold the leather; the engagement of the leather working means following immediately after. Release of the treadle or other operating member immediately interrupts the opening and closing movements of the leather working means and the gripping or clamping mechanism. By reason of these improvements the skill required to operate a machine of this type is reduced to a minimum.

In operation the machine functions as follows:

As soon as the crank shaft 4 is put into rotation the tool arms receive a reciprocating motion; the clamp remains open at rest. The leather is then placed in the machine and the treadle 22 is depressed. The initial movement of the treadle conditions the clamp for operation. Continued movement of the treadle brings the cam 12 into operation so that the tool arms move to and fro in relation to each other during reciprocation and are closed on the back strokes. During the forward strokes the tool arms are opened and the tools 13a, 14a free the leather. The clamp also releases the leather for a short time. During that short interval the operator moves the leather so as to present a fresh portion to the tools. If it is desirable to increase the pressure on any portion of the skin the operator simply steps slightly harder on the treadle 22. Should there be a hole in the leather which would lead to a tear by the tools, the operator would let up on the treadle to such an extent that the tool arms are instantly opened to allow the tools to pass over the hole, it being preferable not to release the treadle completely since, in that case, the work clamping means would also become inoperative.

Having thus described my invention, what I claim as new and desire to secure by Letters Patent of the United States is:

1. In a machine for treating pieces of work, such as leather, a tool for operating on the work piece, a carriage for the tool, mechanism for reciprocating the carriage to move the tool along a surface of the work piece, means to press the tool against the work piece, said means having a movement of translation relative to the carriage and also a rocking movement both during reciprocation of the carriage, and means acting directly on the first-mentioned means to control its movement of translation thereby to effect automatically a predetermined progressive variation in the pressure of the tool on the work piece in the operative stroke of the tool.

2. In a machine for treating pieces of work, such as leather, a tool for operating on the work piece, a carriage for the tool, means for reciprocating the carriage to move the tool along a surface of the work piece, a cam member to press the tool against the work piece to effect treatment of the latter, said cam member being bodily movable with respect to the carriage during reciprocation of the latter, said cam member having also a rocking movement during reciprocation of the carriage to cause proper operation of the tool, and means to control the described bodily movement of the cam member thereby to effect automatically a progressively increasing pressure of the tool on the work piece in its operative stroke.

3. In a machine for treating pieces of work, such as leather, a tool for operating on the work piece, a carriage for the tool, means for reciprocating the carriage to move the tool along a surface of the work piece, a cam member to press the tool against the work piece to effect treatment of the latter, said cam member being bodily movable with respect to the carriage during reciprocation of the latter, said cam member having also a rocking movement during reciprocation of the carriage to cause proper operation of the tool, and means to control the described bodily movement of the cam member thereby to effect automatically a progressively decreasing pressure of the tool on the work piece during the operative stroke of the tool.

4. In a machine for treating pieces of work, such as leather, a tool for operating on the work piece, a carriage upon which the tool is movably mounted, means for reciprocating the carriage to move the tool along a surface of the work piece, a cam member bodily movable relatively to the carriage to provide support for the tool and also movable with the carriage to press the tool against the work piece to effect treatment of the latter, and means associated with the cam member to move the latter relatively to the carriage during reciprocation of the latter to effect a predetermined progressive variation in the pressure of the tool on the work piece during relative movement of the tool and work piece.

5. In a machine for treating pieces of work, such as leather, a tool for operating on a work piece, a carriage upon which the tool is pivotally mounted, means for reciprocating the carriage to move the tool along a surface of the work piece, a cam member bodily movable relatively to the carriage to provide support for the tool and also movable with the carriage to press the tool against the work piece to effect treatment of the latter, and means operating directly on the cam member to change its position relative to the carriage during the operative stroke of the tool, thereby to cause a predetermined progressively increasing pressure of the tool on the work piece in its operative stroke, whereby the operating pressure of the tool gradually increases as the tool approaches an edge portion of the work piece.

6. In a machine for treating pieces of work, such as leather, a tool for operating on the work piece, a carriage, an arm carrying the tool and pivotally mounted on the carriage, means for reciprocating the carriage to move the tool along a surface of the work piece, a cam member bodily movable relatively to the carriage to provide support for the tool and also movable with the carriage to operate on said arm to press the tool against the work piece to effect treatment of the latter, and means operating directly on the cam to change its position relative to the carriage and to control said tool carrying arm to cause a predetermined progressively decreasing pressure of the tool on the work piece during the travel of the tool along a surface of the work piece, whereby the operating pressure of the tool on the work piece decreases as the tool approaches an edge portion of the work piece.

7. In a machine for treating pieces of work, such as leather, a carriage, an upper and a lower arm pivotally mounted on said carriage, co-operating staking tools mounted on said arms, means for reciprocating the carriage and the arms to move the tools relatively to the work piece, means movable with the arms to furnish

- additional support for the latter by which the tools are held in work treating position, means to cause operation of the tools with respect to the work piece to effect treatment of the latter, and means operating directly on the arms supporting means to support the latter for movement along an inclined path thereby to effect automatically a predetermined progressive variation in the pressure of the tools on the work piece in the operative stroke of the tools.
8. In a machine for treating pieces of work, such as leather, an upper and a lower arm, co-operating staking tools mounted on said arms, means comprising a rocking connecting rod to reciprocate the arms to effect movement of the tools relatively to the work piece, a cam member mounted on that end of the connecting rod adjacent to said arms and operative during rocking movement thereof to cause relative movement of the tools to engage the work piece to effect treatment of the latter, and means to lift the cam member progressively with its travel in one direction to effect automatically a progressively increasing pressure of the tools on the work piece during their operative stroke.
9. In a machine for treating pieces of work, such as leather, an upper and a lower arm, co-operating staking tools mounted on said arms, means comprising a connecting rod to reciprocate the arms to effect movement of the tools relatively to the work piece, a cam member mounted on that end of the connecting rod adjacent to said arms and operative to cause relative movement of the tools to engage the work piece to effect treatment of the latter, and means to lower the cam member progressively with its travel in one direction to effect automatically a progressively decreasing pressure of the tools on the work piece during their operative stroke.
10. In a machine for treating pieces of work, such as leather, an upper and a lower arm, co-operating staking tools mounted on said arms, means for reciprocating the arms to move the tools relatively to the work piece, a cam member movable with the arms to cause the tools to engage the work piece to effect treatment of the latter, a support for the cam member, and means operative during the working stroke of the staking tools for adjusting the support with respect to the cam member to effect automatically a predetermined progressive variation in the pressure of the tools on the work piece during staking operations on a given piece of work.
11. In a machine for treating pieces of work, such as leather, an upper and a lower arm, co-operating staking tools mounted on said arms, means to reciprocate the arms to effect movement of the tools relatively to the work piece, a lever pivotally connected with said arms, a cam member pivotally connected to said lever to move with said arms and operative to press the tools against the work piece to effect treatment of the latter, a guideway, a roller on said lever arranged to run on said guideway to support and guide the cam member during reciprocation thereof, and means for adjusting the guideway with respect to the cam member to effect automatically a progressively increasing pressure of the tools on the work piece during their operative stroke.
12. In a machine for treating pieces of work, such as leather, a carriage, co-operating staking tools mounted on said carriage, means to reciprocate the carriage to effect movement of the tools relatively to the work piece, a lever piv-
- totally mounted on said carriage, a cam member pivotally connected to said lever to move with said carriage and operative to cause the tools to engage the work piece to effect treatment of the latter, a guideway, a roller on said lever arranged to run on said guideway to support and guide the cam member during reciprocation thereof, and means for adjusting the guideway with respect to the cam member to effect automatically a progressively decreasing pressure of the tools on the work piece during their operative stroke.
13. In a machine for treating pieces of work such as leather, a tool for operating on the work piece, a carriage for the tool, means for reciprocating the carriage to move the tool along a surface of the work piece, a cam member associated with the carriage and with said reciprocating means to cause pressure of the tool with respect to the work piece to effect treatment of the latter, a support for the cam member, means for operating the support, and adjustable connections between the last-mentioned means and the support to adjust the latter to effect a progressively upward movement of the cam member during the effective stroke of the tool, whereby the tool operates with progressive variation in pressure from a middle portion to an edge portion of the piece of work.
14. In a machine for treating pieces of work, such as leather, a tool for operating on the work piece, a carriage for the tool, means for reciprocating the carriage to move the tool along a surface of the work piece while the latter is held against movement, a cam member associated with the carriage and with the reciprocating means for the carriage to cause pressure of the tool with respect to the work piece during relative movement between the tool and work piece, a support for the cam member, and means to adjust the inclination of said support to effect either a lifting or a lowering of the cam member during the operative stroke of the latter, whereby the pressure of the tool upon the work piece will be progressively changed during travel of the tool and work piece relative to each other.
15. In a staking machine, an upper and a lower arm, co-operating staking tools carried by said arms to engage opposite surfaces of a piece of work, a carriage carrying said arms, a link pivotally connected to the carriage, means for reciprocating the carriage and arms comprising a connecting rod pivotally connected to the link, a cam member mounted on the pivoted end of the connecting rod, a support for the link which serves as a support also for said cam, and means for adjusting the support to effect a progressive variation in the pressure effected by said cam member on the staking tools.
16. In a staking machine, an upper and a lower arm, co-operating staking tools carried by said arms to engage opposite surfaces of a piece of work, a carriage carrying said arms, a link pivotally connected to the carriage, means for reciprocating the carriage and arms comprising a connecting rod pivotally connected to the link, a cam member mounted on the pivoted end of the connecting rod, a support for the link which serves also as a support for said cam, means for adjusting the support to effect automatically a progressive variation in the pressure effected by said cam member on the staking tools, and a manually operable member connected to said support to increase the pressure of the staking operation at the will of the operator.

17. In a machine for treating pieces of work, such as leather, a tool for operating on the work piece, a carriage for the tool, means for reciprocating the carriage to move the tool along a surface of the work piece while the latter is held against movement, a cam member pivotally connected to the carriage and with the reciprocating means for the carriage to cause pressure of the tool with respect to the work piece during relative movement between the tool and work piece, a support for the cam member and carriage comprising a pair of parallel link members pivotally connected at their upper ends to the carriage, a third link member pivotally connected at its upper end to said cam member, a treadle pivotally connected to the lower end of said third link member, the connection between the third link member and the treadle comprising a pin and a slot and the arrangement being such that with the pin at the middle of the slot the third link is parallel to the pair of link members and the cam member is caused to effect substantially uniform pressure of the tool on the work piece during operative stroke of the latter while adjustment of the pin in the slot to either end of the latter causes a progressive variation in the pressure of the tool on the work piece during its operative stroke.

18. In a staking machine, an upper and a lower arm, co-operating staking tools mounted on said arms, a carriage pivotally carrying said arms, a member pivoted to said arms to serve as a positive connection between the arms, spring means between the carriage and one of said arms tending constantly to swing both arms away from each other about their pivot points, means comprising a connecting rod to reciprocate the carriage and the arms carried thereby, and a cam member mounted on said connecting rod and operative when in its normal raised position to effect alternate opening and closing of the staking tools whereby the tools engage a work piece to effect a staking operation during movement of the carriage in one direction and then release the work piece during movement of the carriage in the opposite direction.

19. In a staking machine, an upper and a lower arm, co-operating staking tools mounted on said arms, a carriage pivotally carrying said arms, means comprising a connecting rod to reciprocate said carriage and arms, said connecting rod being pivotally connected to the carriage and having a cam mounted on the pivoted end of the connecting rod, and said cam being arranged to serve when in its raised position as a support for the pivoted arms, and a manually controllable member having connections to lift and to lower said cam whereby the cam may be rendered operative or inoperative at the will of the operator, said cam member being shaped to effect operation of the staking tools on the work piece during the movement of the carriage in one direction and release of the work piece during movement of the carriage in the other direction.

20. In a staking machine, an upper and a lower arm, co-operating staking tools mounted on said arms, a carriage pivotally carrying said arms, a member pivoted to said arms to serve as a positive connection between the arms, spring means between the carriage and one of said arms tending constantly to swing the arms away from each other about their pivot points, means comprising a connecting rod to reciprocate the carriage and the arms carried thereby, a cam member mounted on said connecting rod and adapted when in raised position to support and operate the tool

carrying arms, and a manually operable member having connections to said cam member to lift the latter to operative position whereby the staking tools are caused alternately to engage and to release the work piece during reciprocation of the carriage and the cam, said manually operable member being movable to a position to lower said cam to a point where it ceases to support the tool carrying arms so that the tools remain in open work receiving position during both the back and forth movements of the carriage.

21. In a machine for treating pieces of work, such as leather, a tool for operating on a work piece, a carriage for the tool, means for reciprocating the carriage and tool relatively to the piece of work, a cam member movable with the reciprocating means to press the tool against the piece of work while the machine is in operation, means movable relatively to the carriage during reciprocation thereof for automatically operating the cam member to cause a predetermined progressive variation in the pressure of the tool on the work piece during the operative stroke of the tool, and a manually operable member having connections to provide support for said cam member and to enable the operator to vary at will the pressure of the cam on the tool.

22. In a staking machine, an upper and a lower arm, co-operating staking tools carried by said arms to engage opposite surfaces of a piece of work, means for reciprocating said arms relatively to the piece of work, a cam member movable in an upward direction to support said arms with the tools in work treating position, said cam member being also rotatably movable during travel with the reciprocating means to cause alternate opening and closing of the staking tools relatively to the piece of work while the machine is in operation, means operating directly on the cam member for automatically increasing the pressure of the staking tools on the work piece during their operative stroke, and a manually operable member having connections to the cam member to enable the operator to vary the pressure of the staking operation during the operative stroke of the tools.

23. In a staking machine, a carriage, an upper and a lower arm each pivotally mounted adjacent to one end thereof on said carriage, co-operating staking tools carried by said arms at their other ends to engage opposite surfaces of a piece of work, means for reciprocating said carriage and arms relatively to the piece of work, a cam member movable to engage only the lower of the two arms and rotatably movable during travel with the reciprocating means to cause movement of both arms to effect alternate opening and closing of the staking tools relatively to the piece of work while the machine is in operation, means to predetermine the amount of movement of the cam member in engaging said lower arm thereby to effect automatically a progressively decreasing pressure of the tools on the work piece during the operative stroke of the tools, and a manually operable member having connections directly to said cam member to enable the operator to control the pressure of the staking tools during the operation of said automatically operating means.

24. In a staking machine, an upper and a lower arm, co-operating staking tools mounted on said arms, means for reciprocating the arms relatively to a piece of leather, means movable with the reciprocating means to effect alternate opening and closing of the staking tools with respect

to the piece of leather while the machine is in operation, work clamping means, and means comprising a manually operable member having connections to control the operation of the work clamping means and of said tools in timed relation to each other.

25. In a staking machine, an upper and a lower arm, co-operating staking tools mounted on said arms, means for reciprocating the arms relatively to a piece of leather, a cam member movable with the reciprocating means to effect alternate opening and closing of the staking tools with respect to the piece of leather while the machine is in operation, work clamping means, power means to operate the work clamping means in timed relation to the opening and closing of the staking tools while the piece of leather is being treated, and a manually operable member having connections to said cam and said power means to initiate operation of the cam member and of the work clamping means in properly timed relation to each other.

26. In a staking machine, a carriage, co-operating staking tools mounted on said carriage, means for reciprocating the carriage and tools relatively to a piece of leather, a cam member pivotally mounted on the carriage to effect alternate opening and closing of the staking tools with respect to the piece of leather while the machine is in operation, a guideway to cause effective operation of said cam member when the guideway is lifted, work clamping means, and a manually operable member having connections to lift the guideway and to initiate the operation of the work clamping means in timed relation to each other.

27. In a staking machine, a carriage, co-operating staking tools mounted on said carriage, means for reciprocating the carriage and tools relatively to a piece of leather, a cam member pivotally mounted on the carriage to effect alternate opening and closing of the staking tools with respect to the piece of leather while the machine is in operation, a support for the cam member to cause effective operation of the cam member when the support is lifted, work clamping means, power means to operate the work clamping means in timed relation to the opening and closing of the staking tools while the piece of leather is being treated, and a manually operable member to lift the support and cam member to position for effective operation and to initiate operation of the work clamping means, whereby the staking and work clamping operations take place in properly timed relation to each other.

28. In a staking machine, an upper and a lower arm, co-operating staking tools mounted on said arms, a carriage supporting said arms, means comprising a connecting rod pivoted to the carriage for reciprocating said carriage and arms, a cam member on the pivoted end of the connecting rod to cause a staking pressure of the tools with respect to the work piece during the operative stroke of the tools, a movable work clamping member to hold the work during treatment thereof, a treadle member for controlling the operation of the staking members, and a connection between said treadle member and the movable work clamping member arranged to initiate operation of the clamping member to hold the work against displacement prior to the operation of the staking tools thereof.

29. In a staking machine, an upper and a lower arm, co-operating staking tools mounted on said

arms, a carriage supporting said arms, means comprising a connecting rod pivotally connected to the carriage for reciprocating said carriage and arms, a cam member on the pivoted end of the rod to cause a staking pressure of the tools with respect to the work piece, a support for the cam member, a treadle member, connections between the treadle member and said support effect lifting and lowering of the support thereby rendering said cam member operative or inoperative at the will of the operator, a movable work clamping member, connections between the movable work clamping member and the treadle member, and means to operate the movable work clamping member through said connections to control the work clamping operation prior to the control exercised by the treadle member with respect to said staking tools.

30. In a staking machine, an upper and a lower arm, co-operating staking tools mounted on said arms, a carriage pivotally supporting said arm means for reciprocating the carriage and arm and for effecting alternate closing and opening of the arms whereby the tools alternately engage and release the work piece, a manually operable member having connections to support said arm in their operative position, said member being movable to a position to withdraw support from the arms whereby they remain in open position during reciprocation of the carriage in both directions, so that a piece of work may be introduced at any point in the travel of the carriage work clamping means, and connections between said manually operable member and the clamping means to initiate closing of the clamping means upon the work piece prior to engagement of the work piece by the staking tools.

31. In a staking machine, an upper and a lower arm, co-operating staking tools mounted on said arms, a carriage pivotally supporting said arms means for reciprocating the carriage and arms and for effecting alternate closing and opening of the arms whereby the tools alternately engage and release the work piece, a manually operable member having connections to support said arms in operative position, said member being movable to a position to withdraw support from the arms whereby they remain in open position during reciprocation of the carriage in both directions this arrangement being such that the manually operable member controls the operation of the staking tools, work clamping means, power means adapted to operate the clamping means in timed relation to the closing and opening of the staking tools with respect to the work piece, and connections between said manually operable member and the power means to initiate operation of the latter.

32. In a staking machine, an upper and a lower arm, co-operating staking tools mounted on said arms, a carriage pivotally supporting said arms, means comprising a connecting rod and a cam thereon for reciprocating the carriage and arms and for effecting alternate closing and opening of the arms whereby the tools alternately engage and release the work piece, a manually operable member having connections to support said arms in operative position, said member being movable to a position to withdraw support from the arms whereby they remain in open position during reciprocation of the carriage in both directions, this arrangement being such that the manually operable member controls the operation of the staking tools, work clamping means, an eccentric movable in timed relation to said con-

recting rod, a lever carrying a roll arranged to contact said eccentric, idler rolls mounted on said lever, a flexible cable passing over said idler rolls and connected to the work clamping means, a second lever to which the other end of the flexible cable is connected, and connections between said second lever and the manually operable member whereby movement of the latter initiates operation of the work clamping means in timed relation to the operation of the staking tools.

33. In a staking machine, an upper and a lower arm, a carriage supporting said arms, means for reciprocating the carriage and arms and for causing the arms to swing alternately toward and from each other during reciprocation of the carriage, a staking blade at the forward end of the upper arm, a staking blade at the forward end of the lower arm and lying in a plane inclined upwardly and away from the front of the machine, and a third staking blade carried by the lower arm and lying in a plane inclined upwardly and forwardly to intersect the plane of the second-mentioned blade, the arrangement being such that the third blade produces a milder staking action than the second-mentioned blade.

34. In a staking machine, an upper and a lower arm, a carriage supporting said arms, means for reciprocating the carriage and arms and for causing the arms to swing alternately toward and from each other during reciprocation of the carriage, a staking blade at the forward end of the upper arm, a staking blade at the forward end of the lower arm, a third staking blade carried by the lower arm in spaced relation to the second-mentioned blade, a roll interposed between the two lower blades, a roll mounted in the upper arm to press the work against the lower roll, spring means backing one of said rolls, and means to brake the spring-supported roll after it has yielded a certain distance whereby said roll yields and then becomes resistant to pressure effected by the co-operating roll.

35. In a staking machine, an upper and a lower arm, a carriage supporting said arms, means for reciprocating the carriage and arms and for causing the arms to swing alternately toward and from each other during reciprocation of the carriage, a staking blade at the forward end of the upper arm, a staking blade at the forward end of the lower arm arranged in a plane parallel to the plane of the upper staking blade, and a third staking blade carried by the lower arm and lying in a plane inclined upwardly and forwardly to intersect the first-mentioned planes, the arrangement being such that the third blade produces a milder staking action than the second-mentioned blade.

36. In a staking machine, an upper and a lower arm, a carriage supporting said arms, means for reciprocating the carriage and arms and for causing the arms to swing alternately toward and from each other during reciprocation of the carriage, a staking blade at the forward end of the upper arm, a staking blade at the forward end of the lower arm arranged in a plane parallel to the plane of the upper staking blade, a third staking blade carried by the lower arm and lying in a plane inclined upwardly and forwardly to intersect the first-mentioned planes, a roll interposed between the two lower blades, a roll mounted in the upper arm to press the work against the lower roll, spring means backing said roll whereby the latter may yield, and means to brake the upper roll after it is moved downwardly a certain distance whereby said roll yields and

then becomes resistant to pressure effected by the upper roll.

37. In a staking machine, an upper and a lower arm, co-operating staking tools carried by said arms to engage opposite surfaces of a piece of work, said tools tending constantly to remain in spaced relation to each other, means for reciprocating said arms relatively to the piece of work, a cam member movable with the reciprocating means to cause alternate opening and closing of the staking tools relatively to the piece of work while the machine is in operation, said cam member being also movable between operative position, where it causes periodic closing of the staking tools, and inoperative position where the staking tools will remain open or spaced, and a manually operable member having connections to said cam member to enable the operator to effect gradual movement of the cam member to operative position and also movement to inoperative position wherein the staking tools remain spaced from each other during reciprocation thereof.

38. In a staking machine, an upper and a lower arm, co-operating staking tools carried by said arms to engage opposite surfaces of a piece of work, means for reciprocating said arms relatively to the piece of work, means tending constantly to separate said tools to keep them in work receiving condition, a cam member movable with the reciprocating means to cause alternate opening and closing of the staking tools relatively to the piece of work while the machine is in operation, and a manually operable member having connections to the cam member to enable the operator to control movements of the cam member between operative and inoperative positions whereby the staking tools may operate on the work piece or remain in spaced relation during reciprocation of the arms and tools.

39. In a staking machine, an upper and a lower arm, co-operating staking tools carried by said arms to engage opposite surfaces of a piece of work, means for reciprocating said arms relatively to the piece of work, means tending constantly to separate said tools to keep them in work receiving condition, a cam member movable with the reciprocating means to furnish support for the lower tool carrying arm and to cause alternate opening and closing of the staking tools relatively to the piece of work while the machine is in operation, and a manually operable member having connections to said cam member to enable the operator to move the cam member to operative position and support it there, or to withdraw such support permitting the cam member to move to inoperative position whereby the staking tools remain in spaced position relative to each other during reciprocation thereof.

40. In a machine for treating pieces of work, such as leather, staking tools for operating on a work piece, a carriage for the tools, means for reciprocating the carriage to move the tool along a surface of the work piece while the latter is held against movement, a cam member associated with the carriage and with the reciprocating means for the carriage to cause alternate closing and opening of the tools with respect to the work piece to effect treatment of the latter, and manually controllable means for gradually rendering the cam operative whereby the staking tools periodically engage the work piece, and alternatively inoperative whereby the tools reciprocate with the carriage without closing on the work piece.

41. In a machine for treating pieces of work,

- such as leather, staking tools for operating on a work piece, a carriage for the tools, means for reciprocating the carriage to move the tools along a surface of the work piece, a cam member associated with the carriage and with the reciprocating means for the carriage to cause pressure of the tools with respect to the work piece to effect treatment of the latter, a support for the cam member, a treadle connected to said support 5 to apply pressure to the cam member and therefore to the staking tools, a shaft to which said treadle is secured, and a second treadle secured to the shaft whereby, upon suitable operation of the second treadle, the shaft serves as a torsional spring to apply pressure yieldingly to the staking tools and work piece.
42. In a staking machine, staking tools to engage opposite surfaces of the piece of leather, arms carrying the tools, a carriage furnishing 10 support for and reciprocating said arms and tools, a cam to cause the tools to engage the leather at the beginning of the operative stroke of the tools and to control separating movement of the tools, whereby the latter have an inoperative stroke during which the leather may be moved by the operator relatively to the tools, and 15 a treadle having connections to move said cam bodily to control its operation on the tools, the treadle being operative to vary the pressure of the cam on the tools or to withdraw the cam from its operative position thereby to cause cessation 20 of the work of the tools on the leather, at any point in the operative stroke of the tools.
43. In a machine for operating upon leather, 25 a tool, means for reciprocating the tool over a surface of the leather, means for clamping the leather against movement preliminarily to the operative stroke of the tool, power means for operating the clamping means in timed relation to the beginning and ending of the operative stroke of the tool, and manually controllable means having a direct connection with said clamping means to terminate the action of the clamping means instantly at the will of the operator.
44. In a machine for operating upon leather, 30 staking tools, means for reciprocating the tools to operate on a piece of leather, means for clamp-

ing the leather against movement preliminarily to the operative stroke of the tools, power mean for operating the clamping means in timed relation to the beginning and ending of the operative stroke of the tools, and a manually operable member having a direct connection with the clamping means for initiating a clamping action on the leather preliminarily to the operation of the tools on the leather.

45. In a machine for operating upon leather, tools, means for operating the tool and for reciprocating it over a surface of the leather means for clamping the leather against movement preliminarily to the operative stroke of the tool, power means for operating the clamping means in timed relation to the beginning and ending of the operative stroke of the tool, a manually operable member, and connections between the manually operable member and both the clamping means and the tool operating means so arranged that both the work clamping means and the tool operating means are under the control of the operator to have their operation on the work terminated although the power means for both the clamping means and the tool continue in operation.

46. In a staking machine, a pair of tools for engaging opposite sides of a piece of leather in a staking operation thereon, means for reciprocating the tools, a cam member to effect closing of the tools on the work piece in their operative stroke, said cam member being also movable to control separation of the tools for an inoperative stroke, work clamping means, power means operating both the staking tools and the work clamping means in timed relation to each other to clamp the leather before the staking tools engage it in their operative stroke, a treadle, connections from the treadle to said power means whereby the operator may initiate operation of both the work clamping means and the staking tools, and connections from the treadle to said cam member to move the latter so that the operator may render the cam inoperative to effect closing of the staking tool on the work piece at any point in the operative stroke of the latter through proper control of the said treadle.

GUSTAV A. SCHETTLER.
